Attorney.

UNITED STATES PATENT OFFICE

PAUL FINDEISEN, OF BERLIN, GERMANY

FOUR-STROKE INTERNAL COMBUSTION ENGINE

Application filed April 25, 1931, Serial No. 532,952, and in Germany April 28, 1930.

My invention relates to a four-stroke internal combustion engine with four pistons secured to the ends of an H-shaped connecting member. According to the invention the 5 H-shaped connecting member is directly jointed to the connecting rod and bears at opposite points on the cylinder wall by means of slidable blocks disposed on extensions of the gudgeon pin on which one end of the connecting rod is mounted.

Due to this method of support the connecting member is so guided that it is not subject to transverse stresses and the pressure is 15 favorably distributed in the bearings of the connecting rod.

This method of support also provides a compact construction of the engine, very short pistons may be employed and it is moreover possible to lubricate two cylinders situated opposite each other in the direction of stroke from a common oil-conduit situated in the wall of the casing midway of the cylinders. The oil is distributed by the slidable blocks. To further facilitate the absorption 25 of pressure by the bearings of the connecting rod the arms of the H-shaped connecting member, that constitute each two piston rods, are curved against each other in their middle parts. This curvature moreover provides room for fitting the slide blocks to the H-shaped connecting member. The slide blocks are preferably mounted on the gudgeon pin. The H-shaped connecting member may be 30 built up of single parts or made in one piece.

A construction according to the invention is illustrated by way of example in the accompanying drawing in which

Figure 1 is a section through all the four 10 cylinders of a four-stroke internal combustion engine, and

Figure 2 a section on line A—A of Figure 1.

The four pistons 1, 2, 3, 4 are secured to the four branches *a* of an H-shaped connecting member constituted by several single parts secured together. The two branches *a* of the connecting member, each of which connects two pistons situated opposite each other in the direction of stroke, preferably belong to one single piston rod. The connecting rod

c is directly mounted on the gudgeon pin *b* constituting the cross pin and on the two ends of the said gudgeon pin projecting beyond the piston rods are mounted the blocks *d* which slide on the cylinder wall. The upper and lower cylinders are lubricated from a common central oil conduit *e*. The oil entering the cylinders through the conduit *e* is distributed by the slidable blocks *d* to the piston during its travel. The slidable blocks 55 at the same time distribute the oil around the cylinders.

The slidable blocks favorably distribute the explosion and compression pressures which as a rule act onesidedly on the connecting member. The H-shaped connecting member being not only guided by the pistons, the latter may be very short and light, with consequent reduction of friction, weight and oil consumption, and increase of power.

When the number of cylinders is increased by four additional units, the engine may be built in a V-shape.

What I claim is:—

1. A four-stroke internal combustion engine comprising in combination four pistons travelling in corresponding cylinders, an H-shaped connecting member for securing the said pistons to its free ends, slidable blocks arranged on extensions of the cross pin at both sides of the said H-shaped connecting member for supporting the latter on the casing wall, and a connecting rod connected to the said cross pin.

2. A four-stroke internal combustion engine according to claim 1, with a lubricant conduit in the parts with which the said slid-able blocks of the H-shaped connecting mem-ber engage.

In testimony whereof I affix my signature. PAUL FINDEISEN.
